UNITED STATES PATENT OFFICE.

WILLIAM A. PALMER, OF DUBUQUE, IOWA.

FLAT-OPENING BOOK.

SPECIFICATION forming part of Letters Patent No. 528,340, dated October 30, 1894.

Application filed June 27, 1894. Serial No. 515,869. (No model.)

To all whom it may concern:

Be it known that I, WILLIAM A. PALMER, a citizen of the United States, residing at Dubuque, in the county of Dubuque and State 5 of Iowa, have invented certain new and useful Improvements in Flat-Opening Books; and I do hereby declare the following to be a full, clear, and exact description of the invention, such as will enable others skilled in the art to 10 to which it appertains to make and use the same.

My invention consists in an account, blank or other flat opening book, comprising in its construction zig zag folded guards, all of the folds of the same width and forming two forward stitching loops to the outer edges of 15 which the leaf-sections are attached in pairs and one rear loop, which is sewed to the parchment or back band in preparing the book for binding, this specific and peculiar construction 20 extending throughout the book.

By my invention the leaf-sections are sewed to the guards before the sheets or guards are folded, by sewing one of the leaf-sections to the inner or forward edge of one of the guards 25 and then turning around the guard and sewing the other leaf-section to the inner or forward edge of the other loop of the guard, then when folded, they form a single book-section composed of two double-sections attached to 30 the edges of the inner or forward loops and a single loop for sewing the book-section to the parchment bands or bridge straps whereby, the amount of sewing required for uniting the guards with sections attached, to the back of 35 the cover or to the back band or straps is reduced one half or one third in a book of a given number of sections; the reduction in the amount of sewing being according to the number of leaves composing the respective sections. Furthermore the back edges of the flat 40 portions of the guard are concealed, and the book when thus constructed will be composed of a given number of independent book-sections, each section of which will be composed 45 of double leaf-sections attached to the inner or forward edges of the two loops of the same guard and will be entirely flat-opening. By this mode of construction, it will be readily seen that there is no necessity for reinforcing 50 the guard with canvas or cloth as the loops of the guard to which the leaves are sewed are of as many thicknesses as there are double

leaves in each leaf-section. Books made in this manner are exceedingly strong and durable.

In the accompanying drawings, Figure 1. is 55 a perspective view of one of a series of guards which are employed in the construction of the book. Fig. 2. is an end view showing one of the guards with the leaf-sections stitched to it. Fig. 3. is also an end view of three guards, six 60 leaf-sections and a back band or bridge strap united by stitching and sewing; and Fig. 4. is a broken view of a bound book. The cover of the book is shown in cross section and five 65 guards and ten leaf-sections in elevation, the whole being stitched, sewed, and bound together.

A in the drawings, indicates the lids of the cover, B the back, and C one of the bridge straps or parchment or back bands of the 70 book.

D indicates the guard; E, E' the leaf-sections; F, F' the stitching between the guards and the sections, and G the sewing between the guards and back bands or bridge straps 75 of the book.

The guards D throughout the book are formed preferably by folding paper of substantially the same thickness and the same number of pieces as compose each leaf-section E, E'.

I have found that a convenient number of leaves for each leaf-section to be six or three sheets folded at their center, and the guard for such section would be composed of three 85 pieces of paper, which greatly adds to its strength. When thus constructed each guard has two inner or forward stitching loops a, a' for receiving the thread for which a pair of leaf-sections E, E' are attached to each guard 90 as indicated at F, F' and the outer or rear loop a² for receiving the cord or thread by which the guard is attached to the parchment bands or bridge straps C, C of the back B of the book as shown. Each of the guards when 95 folded has a doubled intermediate portion c and right and left hand single flap portions d formed of the same material and of the same thickness as C. The flap portions have their outer or rear edges terminated just at the 100 back bands or straps, and while they are left free will be concealed when the book is opened.

The respective guards are wholly independ-

ent of one another and when the book is finished and closed the flap portions of one guard will lie against the flap portions of another guard, but not connected together, and the intermediate double portion will lie flat between the flaps of the guard, the construction being followed throughout the book, and all being held firmly in their place in the process of binding.

10 By my invention flat opening books can be constructed at considerable less cost as there is much less sewing to unite the sections into a book than under other modes of construction, while their durability and convenience 15 are insured.

What I claim as my invention, and desire to secure by Letters Patent, is—

A flat opening book having independent guards each formed by folding the material 20 so as to make a doubled intermediate portion

which terminates in an outer or rear loop, and also to make right and left hand flap portions which with the intermediate portion form two inner or forward stitching loops, said book also having leaf-sections stitched in pairs to each 25 guard, forming a single book-section and the sections and guards being sewed to the back hand or bridge straps by threads passed through the outer loops of the intermediate doubled portions of the guards and the flap 30 portions of the respective guards lying flat-wise against one another when the book is finished and closed, substantially as described.

In testimony whereof I affix my signature in presence of two witnesses.

WILLIAM A. PALMER.
